UNITED STATES PATENT OFFICE.

JOHN F. GRANDY AND CHARLES FRANK GRANDY, OF GREENVILLE, SOUTH CAROLINA.

CROSS-TIE.

No. 877,328.

Specification of Letters Patent.

Patented Jan. 21, 1908.

Application filed May 16, 1907; Serial No. 373,928.

To all whom it may concern:

Be it known that we, JOHN F. GRANDY and CHARLES FRANK GRANDY, citizens of the United States, and residents of Greenville, in the county of Greenville and State of South Carolina, have invented an Improvement in Cross-Ties, of which the following is a specification.

Our invention is an improvement in cross ties, and consists in certain novel constructions and combinations of parts hereinafter described and claimed.

Referring to the drawings forming a part hereof, Figure 1 is a plan view of a portion of our improved tie, and a portion of the rail resting thereon. Fig. 2 is a section on the line 2—2 of Fig. 1. Fig. 3 is a section on the line 3—3 of Fig. 1; and Fig. 4 is a detail perspective view of a portion of the spike receiving tube or casing.

In the present embodiment of our invention, the tie comprises a body *a* of concrete or other plastic material reinforced by channel plates *a'* upon its upper and lower faces, the flanges *a''* of the channel plates engaging the sides of the tie and being embedded in the substance thereof as clearly shown in Fig. 3. Openings *a³* are arranged in the side of the tie for the insertion of grabs or picks for convenience in handling the tie.

A plurality of tubes or tubular casings *B* are arranged in the body of the tie, the said tubes being arranged in pairs one in each end of the tie, the members of the pairs being spaced apart and offset laterally from each other, for receiving the base *e* of the rail *E* therebetween. The reinforcing plates *a'* are each provided with openings *a⁴* registering with the open ends of the casings, and the opposite side walls *b* of the casing are extended through the opening and flanged as at *b⁴* for engaging the outer face of the said plates.

Each of the casings *B* is provided on its inner wall near each end thereof, with a pocket or recess *b'*, and the wall of the recess or pocket remote from the adjacent face of the tie is inclined toward the interior of the casing as at *b²* for a purpose to be hereafter described.

The spike *C* consists of a wedge-shaped body *c* having at the thin end thereof a lip *c'* for engaging the base *e* of the rail, and at the other end a lug *c²*, whose upper face is beveled as at *c³* for co-operating with the inclined wall of the recess or pocket. The

spike is locked in position by a wedge-shaped locking pin *D*, having a lip *d²* at its thick end for convenience in manipulating the said pin.

In using our improved tie, the ties are arranged in the ordinary manner, and the rails laid thereon. After the rails are in position, the spikes *C* are inserted in the tubes or casings and arranged with the lip engaging the base of the rail and with the lug engaging the recess or pocket remote from the face of the tie upon which the rail rests. The locking pin is then inserted and driven into the casing a sufficient distance to securely lock the spike in place. The inclined upper surface of the lug and the inclined wall of the pocket, provide for slight variations in the length of the spike, and aid in drawing the rail base down firmly upon the tie. Since a pocket or recess is provided at each end of the tube or casing, it is immaterial which face of the tie is upward when they are placed in position since the spike is adapted to be inserted from either end of the tube. By removing the locking pin, the rail may be disengaged from the tie when it is desired for any purpose.

While only two tubes or casings are shown at each end of the tie, it is obvious that more might be made use of, if desired, on curves or wherever extra bracing of tie might be necessary.

We claim:

1. A tie comprising a concrete body having reinforcing channel plates on its upper and lower surfaces, the flanges of the plates engaging the sides of the tie, tubular casings arranged within the body, said casings being arranged in pairs near each end of the tie, the members of each pair being spaced apart and offset laterally from each other, said reinforcing plates being provided with openings registering with the ends of the tubular casings, the ends of opposite side walls of the casings being extended through the openings and flanged for engaging the outer faces of said plates, each of said casings having pockets in the inner wall thereof, the pockets being spaced apart from each other and having the wall remote from the adjacent face of the tie inclined toward the interior of the casing, a wedge-shaped spike provided at its thin end with a lip for engaging the rail base, and at its thick end with a lug for entering the pocket remote from the surface of the tie upon which rests the rail, the upper face of the lug being inclined for co-operating with the inclined wall of the pocket, and a wedge-

shaped locking pin arranged between the spike and the outer wall of the casing, said pin being provided with a head on its free end.

- 5 2. A tie having a body portion composed of plastic material, and provided with tubes arranged transversely thereof in pairs near each end of the tie, the members of each pair being spaced apart and offset laterally from each other, each of said tubes being provided with pockets in its inner wall, the pockets being spaced apart from each other and having the wall remote from the adjacent face of the tie inclined toward the interior of the casing, 10 a wedge-shaped spike provided at its thin end with a lip for engaging the rail base and at its thick end with a lug for entering the pocket remote from the surface of the tie upon which rests the rail, the upper face of 15 the lug being inclined for coöoperating with the inclined wall of the pocket, and a wedge-shaped locking pin between the spike and the outer wall of the tube.
3. A tie having a body portion composed of plastic material, and provided with tubes arranged transversely thereof in pairs near each end of the tie, the members of each pair being spaced apart and offset laterally from each other, a wedge-shaped spike provided 20 at its thin end with a lip for engaging the rail base and at its thick end with a lug for entering the pocket remote from the surface of the tie upon which rests the rail, the upper face of the lug being inclined for coöoperating with

the inclined wall of the pocket, and means 35 engaging the spike and the wall of the tube for locking said spike in position.

4. A tie having a body portion composed of plastic material, and provided with tubes arranged transversely thereof in pairs near 40 each end of the tie, the members of each pair being spaced apart and offset laterally from each other, each of said tubes having pockets in its inner wall, the pockets being spaced apart from each other and having the wall 45 remote from the adjacent face of the tie inclined toward the interior of the casing, a spike provided at one end with a lip for engaging the rail base, and at the other with a lug for entering the pocket remote from the 50 surface of the tie upon which rests the rail, and means for locking the spike within the tube.

5. A tie of the class described, having vertical tubular openings therethrough, said 55 openings being arranged in pairs at each end of the tie, and each provided in its inner wall with pockets, a spike within each opening, said spikes being provided with a lip for engaging the rail base, and with a lug for entering the pocket remote from the face of the tie upon which the rail rests, and means for locking the spikes in place.
